UNITED STATES PATENT OFFICE.

DAVID K. JACKMAN, OF POUGHKEEPSIE, NEW YORK, ASSIGNOR TO THE DUPLEX VENDOR COMPANY, OF POUGHKEEPSIE, NEW YORK, A CORPORATION OF NEW YORK.

VENDING APPARATUS.

SPECIFICATION forming part of Letters Patent No. 764,360, dated July 5, 1904.

Application filed October 28, 1902. Serial No. 129,084. (No model.)

To all whom it may concern:

Be it known that I, DAVID K. JACKMAN, a citizen of the United States, residing at Poughkeepsie, in the county of Dutchess and State of New York, have invented certain new and useful Improvements in Vending Apparatus; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 This invention relates to vending apparatus, and contemplates the provision of a machine in which the goods—cigars, for instance—are displayed so as to be visually inspected by the customer and are designed to be handled and examined to allow the customer to make a selection, the construction of the machine being such, however, that the goods can only be removed upon the prepayment of a proper coin and in number or quantity dependent upon 25 the value of the coin.

20 The invention further contemplates the provision of a machine having different compartments for goods of different values, with coin-controlled mechanism common to both compartments and controlling the delivery of goods from either compartment at the option of the customer.

25 The invention still further contemplates the provision of a novel flexible guard or shield which is adapted to be manipulated by the hand of a customer and by which the customer is enabled to select and remove any sample of the goods he desires without the possibility of surreptitiously abstracting them, also the provision of a shutter automatically operated and controlling access to said guard.

30 The invention still further contemplates the provision of mechanism adapted to be controlled by the deposit of coins of different denominations in such manner as to effect the discharge of a greater or lesser quantity or number of goods according to the value of the coin and also to effect the delivery of goods

from either compartment when coins of the same denomination are applicable for the purchase of goods from both, while at the same time preventing the discharge of goods from one compartment when the coin deposited is usable only in the purchase of goods from the other compartment.

35 The invention furthermore contemplates certain other distinguishing parts, features of construction, and combination of parts, as will be hereinafter more fully described, and particularly pointed out in the appended claims, reference being had to the accompanying drawings, in which—

40 Figure 1 is a front elevation of a vending apparatus embodying my invention. Fig. 2 is a top plan view of the same. Fig. 3 is a vertical section taken on line 3-3 of Fig. 1. Fig. 3' is a section on line 3'-3' of Fig. 4. Fig. 3" is a section on x-x. Fig. 4 is a section taken on the line 4-4 of Fig. 2 looking toward the rear of the case. Fig. 5 is a similar section with the coin-controlled mechanism removed and looking toward the inner side of the front wall of the case. Fig. 6 is a vertical section through one of the shutters and the co-operating flexible guard or mitten. Fig. 7 is a detail view showing the mitten extended. Fig. 8 is a top plan view of the coin-controlled feed mechanism, the delivery-tray being removed. Fig. 9 is a side elevation of the same. Fig. 10 is a vertical longitudinal section through the coin-slides guide, the coin-chute 65, slot 98, casing 59, and the coin-slides, the slide-bar 58 appearing partly in elevation. Fig. 11 is a detail view of the clutch mechanism which controls the operation of the feed tray or table, showing the positions assumed by the same on the movement of the operating-shaft to the left or right. Fig. 12 is a transverse section through the vending mechanism, showing a detail view of the milled gear and coacting parts. Fig. 13 is a horizontal section of the parts shown in Fig. 10, and Fig. 14 is an inner side elevation of the rack-bar which operates the coin-slides. Fig. 15 is a detail side elevation of the toothed wheels or disks 74 and 75. Fig. 16 is a hori-

Sliding Pusher.

zontal section on line 16 16 of Fig. 9, showing the coin-slides and communicating discharge-slot 98; and Fig. 17 is a detail view of the wheel or disk 74.

5 Referring now more particularly to the drawings, the numeral 1 represents a box or casing provided with transparent top and side panels 2 and 3 and having at the rear doors 4, which afford access to the interior thereof, 10 each of said doors consisting of a main section 5 and a swinging section 6, the latter being hinged to said main section. The main section has a sliding connection with the rear portion of the case, which forms a doorway, 15 and the two doors thus constructed are adapted to close the spaces on opposite sides of the center of the casing. It will be seen that by forming each door of a sliding section and a hinged section upon throwing the hinged- 20 door sections open access will be afforded to the center of the case and that if it be desired to fully open the doorway on either side of the center this may be accomplished by simply folding back the hinged section of one 25 door, swinging out the hinged section of the other door, and sliding the latter door up against the main section of the first-named door. It will therefore be apparent that the doors may be conveniently adjusted to give 30 partial or full access to either or both sides of the center of the casing and that in their open position the doors are adapted to occupy but little room, as the swinging sections may, if desired, be folded close up against the 35 outer sides of the sliding sections.

The interior of the box or casing is divided into compartments 7 and 8 by a cover 9, which incloses the vending mechanism, and by a transparent panel or partition 10, which 40 extends between the top of said cover and the top of the casing. As shown, the partition 10, which is preferably made of glass, is fitted in grooved guideways 11, fixed to the top of the case and to the upper surface of the cover, 45 so that by sliding the partition rearwardly it may be disengaged from the grooved guideways and the removal of the cover 9 through the doorway at the rear of the case permitted.

The front of the casing is provided with 50 glass panels 12 and three metallic panels 13, 14, and 15, the panels 13 and 14 being provided with openings 13' 14', affording access to the two compartments 7 and 8 on opposite sides of the partition 10, these openings being closed by vertically-sliding doors or shutters 16 16'. The panel 15 is slotted to form a delivery-opening 17, a coin-slot 18, and an observation-opening 19, through which latter the coin contained in the coin-receptacle of 55 the coin-vending mechanism is temporarily displayed prior to its deposit into the money-drawer, as hereinafter described.

The shutters 16 16' are mounted to slide vertically in similar guideways 20 and are connected to two sets of toggle-jointed levers 21

21', each adapted to engage a pair of levers or arms 22, provided at their inner ends with intermeshing pinions 23, mounted upon shafts 24, journaled in a block or bearing 25, fixed to the bottom of the casing. The arms 22 are 70 provided at their outer ends with right-angled extensions 26, which are adapted to bear against the outer sides of the lowermost pair of levers of the said toggle-levers, and when motion is transmitted thereto in an inward direction to extend said levers, thereby closing the connecting-shutter 16 or 16'. One arm of each set of arms 22 is provided with an extending-crank 27 27', to which cranks are pivoted the operating-rod 28 28', extending toward the center of the case and sliding through suitable guides 29, said rods having at their inner ends V-shaped contact portions 30 30'. A bearing-bracket 31 forms one of the bearings for a short rock-shaft 32, which projects through the panel 15 and to the outer end of which is connected an operating-handle 33, which normally stands in a vertical position, as shown in Fig. 1. This shaft carries a cam-segment 34, which bears upon the V-shaped contact portions 30 30' of the operating-rod 28 28'. 85

When the handle 33 stands in a neutral or vertical position, as shown in Fig. 1, the sides of the cam-segment 34 bear upon the V-shaped contact-pieces 30 30' of the two operating-rod 28 28' and hold said rods projected—that is, moved outwardly to their fullest extent toward the sides of the case—this action causing the arms 22 to be thrown upwardly and 90 their right-angled extensions 26 to be brought to bear against the lowermost toggle-levers of each set, thus forcing said levers to spread out and move the doors or shutters 16 16' upwardly, so as to close the openings 13' 14' in 105 the panels 13 and 14. By this means the two shutters are normally held closed. When the handle 33 is turned in one direction or the other, however, one of the doors will be opened through the medium of the connecting means 110 before described to admit access to one of the compartments 7 or 8. Assuming that the handle 33 is moved to the right, it will of course be understood that the cam 34 will be moved out of engagement with the V-shaped contact-piece 30', allowing the rod 28' to be forced inwardly under the combined action of a spring 35', connected with the toggle-levers 21', and the weight of the shutter 16', which when pressure is removed from the levers 21' tends to drop down by gravity, this action 115 causing the downward movement of the connecting set of arms 22 to a horizontal position and the opening of the shutter 16. 120

When the handle 33 is moved in a reverse 125 direction or to the left, the cam-segment 34 will be moved out of engagement with the V-shaped contact 30 of the rod 28, allowing the shutter 13 to open in a similar manner; but in each case the movement of the cam-segment 130

in a direction to open one shutter will maintain it in engagement with the operating-rod of the other shutter, thus keeping the latter-named shutter closed, and at the same time 5 the restoration of the cam-segment to a neutral position will cause the operation of the connections to force both shutters closed and to lock them closed until the handle is again operated to effect their opening in the manner previously described.

The two compartments 7 and 8 are designed to hold goods or commodities—say cigars—of different values, and it is contemplated to place within the compartment 7 cigars designed to be sold at the rate of five cents a piece, two for ten cents, or five for a quarter, while it is designed to place within the compartment 8 cigars selling at the rate of ten cents each or three for twenty-five cents. 15 Other goods of different values may, however, be placed within the two compartments for sale, and the machine is not limited to the sale of cigars.

The transparent panels of the case permit 20 the customer to visually inspect the goods, and the openings 13' 14' are provided to enable the customer to insert his hand within either compartment for the purpose of making a selection of one or more articles or 25 samples of the goods, means being provided to enable the customer to manipulate the goods without the possibility of surreptitiously abstracting them. To this end a shield or guard 36 in the form of a flexible pocket 30 or mitten is arranged in the rear of each opening 13' 14' and is adapted to receive the thumb and fingers of the hand of the customer to enable him to pick out or select such cigars as he may desire and place them in position 35 to be delivered at the front of the machine without permitting him to have direct manual contact therewith or to draw any of the goods out of either one of the said openings. The pocket is constructed of any suitable flexible 40 material—such as fabric, leather, interwoven links, or silk—and is formed at its mouth with a hem 37 to receive the larger coil of a spiral spring 38, clamps 39 being provided to rigidly secure the spring and pocket to the rear or 45 inner side of the panels 14 or 15. These clamps or fastenings 38 are removable to enable the pocket to be readily detached and others attached, which operation is frequently necessary for laundry purposes. It will be 50 seen that the spiral spring 37 allows the pocket to be extended so that it may be projected inwardly a sufficient distance to enable the customer to reach the cigars within any of the boxes in either of the compartments and that 55 when the hand of the customer is removed from the pocket the spring will automatically close said pocket up against the rear side of the front wall of the casing.

The cover 9 forms a three-sided inclosure 60 for the coin-controlled vending mechanism,

which latter is mounted upon a suitable base 40 and is provided with a bracket 40' to receive the inner end of the rock-shaft 32, carrying the segmental cam 34. From this base rise spaced side walls 41, connected by suitable rods 42 and the shafts of the gearing, hereinafter described. The rods 42 are formed with openings for the reception of pins upon a platform or table 43, which closes the space between the side walls of the frame at the 75 rear of said frame and forms a bottom for the grated guard or table 78, hereinafter described. At the front of the frame between the side walls is arranged a receiving-compartment 44, into which the goods are discharged and which 80 communicates with the delivery-opening 17. This receiving-compartment is provided with a hood 45, which allows the goods to pass to the front thereof, but at the same time prevents the introduction of a hand or implement from the front of the machine to the controlling parts of the vending mechanism effecting the feed of the goods to said compartments, so that access cannot be obtained to the vending mechanism from either compartment of the delivery-opening to interfere 85 with the proper action of the mechanism and delivery of the goods.

The vending mechanism is so constructed that the customer by the operation of the handle 33 to the right or left may control the delivery of goods from either compartment 7 or 8 and so that the proper amount or number of goods of different value will be delivered in proper ratio or proportion, according to the 90 denomination of the coin deposited within the slot 18 and the direction in which the handle 33 is moved to discharge a certain amount of goods from the compartment 7 or the compartment 8. To this end in the present instance I have so constructed the coin-vending mechanism as to enable a customer to obtain from the compartment 7 cigars to the 95 number of one for five cents, two for ten cents, or five for twenty-five cents and from the compartment 8 cigars to the number of one for ten cents or three for twenty-five cents and have so devised the mechanism as to prevent the outlet of any goods from one compartment when the handle 33 has been properly manipulated, and the coin inserted is usable to obtain goods only from the other compartment.

The coin mechanism having the above-named capabilities is constructed as follows: 100 A shaft 46 extends horizontally from front to rear of the frame of the vending mechanism and is journaled in suitable bearings 47, secured to the base 40. At its forward end this shaft carries a gear-wheel 48, which meshes 105 with a pinion 49 on the shaft 32, whereby when the handle 33 is moved in one direction or the other the shaft 46 will be rocked to the right or left, as the case may be. At its rear end the shaft 46 carries a mutilated gear 50, 110

184. CHECK CONTROLLED APPARATUS.

Draft

Sliding Pusher.

the teeth of which are beveled and extend approximately half around its circumference. This gear is adapted to mesh with either one of the two pinions 51 and 52, mounted upon a counter-shaft 53, journaled in bearings 54, said counter-shaft also carrying a gear-wheel 55 and having connected thereto one end of a spring 56, coiled about the same and secured at its outer end to the base 40, said spring 10 acting to restore the parts to their normal position, as hereinafter described.

The gear-wheel 55 meshes with rack-teeth 57 on the under side of an operating sliding bar 58, which moves longitudinally within a guide-casing 59, secured upon the outer side of one of the said side walls 41 of the frame of the vending mechanism. This bar 58 is provided at its forward end with a coin-receiving slot 59', and above the same are disposed a series of coin-slides 60, 61, 62, and 63, which are flanged to slide in guide-grooves 64, formed in said casing 59. These slides coact to form a compound clutch and to this end are formed at their forward ends with similar coin-slots 60', 61', 62', and 63', which are adapted to coöperate with the slot 59'. The slide 60, which is located immediately above the bar 58, is notched or recessed to form a shoulder 60", while the slide 61, immediately 30 above, is slotted at its outer end and formed with an inclined face 61", not so abrupt as to form a shoulder. The slide 62 is above the slide 61 and is longitudinally slotted at its outer end to a point adjacent to the slot 62', being separated therefrom by a short wall, which forms a shoulder 62". The uppermost slide 63 is longitudinally grooved on its under side to form a shield or housing for a pivoted pawl or dog 63", adapted to coöperate with 40 said shoulders to effect the movement of the slides to control the action of the vending mechanism according to the character or denomination of the coin inserted in the slot 18.

The guide 59 carries a coin-chute 65, which 45 receives the coins deposited in the slot 18 and conveys the same to the slots 59' 60', &c., in the several slides, and said guide 59 is also provided with a discharge-slot 66, connecting with a chute 67, leading to a coin-receiving chamber 68 below the front part of the goods-receptacle 44 at the front of the vending mechanism. This coin-receiving chamber 68 is provided with a transparent panel and is arranged in the rear of the observation-opening 19 and provided with a tilting bottom 69, which is adapted to be operated to discharge the coin into a money-drawer 70, said drawer being located beneath the base 39.

The slide 63 is provided with rack-teeth 71, 60 which mesh with a gear-wheel 72 on a shaft or arbor 73. This shaft or arbor 73 carries a toothed wheel or disk 74, adapted to mesh with a wheel or disk 75 on a parallel shaft 76, which shaft 76 is provided with a pair of gear-wheels 77. These gear-wheels 77 are adapted

to transmit motion to a carriage-like guard or table 78, provided with wheels or rollers 79 to run along tracks 80 on the side walls 41. The guard or table 78 is provided with rack-toothed flanges 81 to mesh with the gear-wheels 77 and has an imperforate portion 82 and a grated portion 83, the openings in which correspond in number to the maximum capacity of the machine in effecting the feeding of a certain number of cigars at a time to 75 the receiving - compartment 44. In other words, but five cigars may be discharged from the machine at one time, and the grated portion of the guard or table forms a corresponding number of openings, one for the reception 80 of each cigar.

The cover 9 is provided with a grating 84, similar to the grating 83 of the guard or table and having a corresponding number of openings. Normally the imperforate portion 85 82 of the guard or table lies immediately below the grating 84 of the cover, so that no cigars may be inserted within the openings in the grated portion of the table; but when the vending mechanism is operated one or more 90 of the openings in the guard or table will be brought to correspond with the openings in the grating 84 of the cover, according to the denomination of the coin inserted to pay for one, two, three, or five cigars. When, for 95 instance, a nickel is inserted in the slot 18 and drops within the slots 59', &c., of the slides of the coin-vending mechanism and the lever 33 is turned to the right, the action of the cam 34 will first throw open the shutter 100 16', and then as the gear 48 receives motion from the pinion 49 the shaft 46 will be turned to the left and the mutilated gear 50 will operate the pinion 51, thereby turning the gear-wheel 55, which communicates motion to the operating-slide 58. On the outward movement of this slide the nickel is carried with it and bears against the slides 60, 61, and 62, causing said slides to move with the slide 58. The slide 58 and the slides 60, 61, and 62 110 move outwardly a determined distance until the pawl 63" of the rack-bar 63 engages the shoulder 62" of the slide 62, whereupon the slide 63 is caused to move with the other slides and motion is transferred by the rack-teeth 71 to the gear-wheel 72, thence through the wheels or disks 74 and 75 to the shaft 76 and gear-wheel 77, whereby the table 78 is moved a certain distance to expose one of the openings in its grated portion, allowing the customer to insert one cigar therein, the cigar being supported by the table 43. When the lever 33 is restored to its normal position, the operation of the parts is reversed and the guard 78 is retracted, forcing the cigar from the table 43 into the receiving-compartment 44, from whence it is removed by the customer.

The operating slide-bar 58 is provided with a series of teeth or notches 85, engaged by a 130

pawl 86, pivoted upon the frame of the vending mechanism so as to swing freely in either direction, said pawl acting to prevent the bar from being forced back before the stroke necessary to operate the machine has been completed, thus preventing a person from manipulating the machine to obtain more cigars than he is entitled to.

At each end of the toothed portion 85 the bar 58 is recessed to form shoulders 87 and 88. These shoulders are inclined in reverse direction, and when the bar 58 moves rearwardly the shoulder 87 swings the pawl into position so that it will engage the teeth or notches in the rear of its pivotal connection and prevent the bar from being retracted in the manner stated. When the bar reaches the limit of its rearward movement, the pawl drops down into the recess forming the shoulder 88 and 20 rides upon said shoulder, which reverses the pawl, allowing it to ride over the teeth 85 as the pawl is retracted. By this construction the pawl is made reversible, so as to allow the bar to move freely backward after it has 25 moved outward to its fullest extent, but not until then, as the reversal of the pawl by the shoulder 88 is necessary to adapt it to ride backward over the teeth 85 to permit the bar to become restored to its normal position.

The bar 58 is provided with a finger or projection 89, which upon the inward movement of the bar restores the slides to their normal position and which upon the outward movement of the bar is adapted to engage a contact-arm 35 90, connected to a rock-shaft 91, carrying a bell-hammer 92, adapted to strike a gong 93, indicating that the coin-vending mechanism has performed its correct operation after the deposit of the coin and the operation of the 40 lever 33 and after the tray has been moved to allow the required number of cigars to be deposited within its grated portion for ejection. The coin deposited remains within the coin-receiving chamber 68 until the machine 45 is again manipulated, when upon the outward movement of the rack-bar 63 the tilting bottom 50 69 of said chamber is operated to drop the coin into the money-drawer 70. To this end the rack-bar 63 is provided with a pivoted 55 pawl or catch 94, having a hooked end 94^a, which when the bar moves outward engages one arm of a bell-crank lever 95 and tilts said lever and which when the bar moves back to its normal position rides over said lever and becomes automatically set for further operation. This pawl 94 has a lateral flange 94^b, (see Fig. 12,) which rests on the upper edge of the outer wall of casing 59, whereby said pawl is normally supported in a substantially horizontal 60 position, so as to engage the lever 95 upon the outward movement of said bar 63. As the bar 63 moves rearwardly or outwardly the hooked end 94^a of pawl 94 engages the upper end of the lever 95 and tilts said lever rearwardly, 65 allowing the hooked end of the pawl to ride

over it and pass to the rear of it with the bar 63. The hooked end 94^a of the pawl has a curved or beveled nose, which upon the forward or retractive movement of the bar 63 comes in contact with the lever 95 and tilts 70 said lever upwardly, allowing said hooked end 94^a to clear said lever, so that when the bar 63 reaches the limit of its retractive movement the pawl 94 will drop down again to its normal position (shown in Fig. 9) in readiness to again operate lever 95 upon the next 75 succeeding outward movement of the bar 63.

The bell-crank lever 95 is adapted when tilted to force upwardly an arm 96, connected to a rock-shaft 97, which in turn is connected 80 to the tilting bottom 69, whereby when the bell-crank lever is operated said bottom will be tilted to deposit the coin into the drawer 70.

The construction of the slides 58, 60, 61, 85 62, and 63 is such as to move the guard or table 78 the distance of one, two, three, or five openings of its grated portion, according to the denomination of the coin inserted in the slot 18 and the direction in which the handle 33 is operated.

By reference to Fig. 10 it will be seen that the depth of the slots 59' and 60' is such as to receive a coin of the denomination of one dime and that said coin when deposited will form a connection between the slides 58 and 60. Consequently when the slide 58 is drawn out the slide 60 will move therewith without operating the slide 63 until the pawl 63^a engages the shoulder 60^a, whereupon the slide 63 will be moved a distance necessary to bring two of the 95 openings in the grated portion of the guard or table beneath the grated portion of the cover 9. This is the case when the handle 33 is turned to the right, allowing the customer to place two cigars within the ejecting mechanism for discharge; but when the handle 33 is moved to the left the tray or table is caused by mechanism hereinafter described to move a distance only to bring one of its receiving-openings beneath the grated portion of the 100 cover 9.

The depth of the slots in the four slides 58, 60, 61, and 62 is sufficient to receive a nickel or five-cent piece, which will form a connection between said slides adapting them to move in unison. When the slide 58 is moved rearwardly by the handle 33 through the medium of the mechanism before described, the slides 60, 61, and 62 move outwardly therewith without moving the slide 63, until the pawl 63^a engages the shoulder 62^a, whereupon a movement is imparted to the slide 63 a distance approximately equivalent to one-half the distance afforded by the movement of the slide 60 when a dime is inserted, thus causing 115 the guard or table 78 to move approximately one-half the distance and to bring only one of its receiving-openings below the grated portion of the cover 9, thus allowing only one cigar to be inserted for removal from the 120 machine.

Reciprocating Parts,

characteristic operation being permitted upon the insertion of a nickel and by the movement of the handle 33 to the right only to enable a cigar to be discharged from the compartment

5 7. When a quarter of a dollar is inserted, it fully occupies the depth of the slots 59', 60', 61', 62', and 63" and forms a connection between all of the slides, thus adapting them to move in unison, and upon the outward movement of the slide 58 slide 63 begins immediately to communicate motion to the gear-wheel 72, thus moving the guard or table 78 to its fullest extent—namely, to an extent sufficient to bring all of the openings of its 15 grated portion beneath the grated portion of the cover 9, allowing five cigars to be inserted therein from the compartment 7. This is the case when the handle is turned to the right; but upon the movement of the handle to the 20 left the guard or table is operated to an extent to bring only three of the receiving-openings of its grated portion beneath the grating in the cover 9 by mechanism herein-after described.

25 If an attempt should be made to operate the machine by the deposit of a coin of a size less than a nickel and greater than a dime—say a penny—the movement of the bar 58 would not be interfered with and the guard 30 78 would not be operated, and consequently no cigars can be discharged from the machine.

When a penny is inserted, it occupies the depth of the slot in the three slides 58, 60, and 35 61 and forms a locking connection between said slides to cause them to move in unison upon the outward movement of slide 58. This outward movement of slide 58 would, however, not at any point transmit motion to the slide 63, 40 for the reason that the pawl 63^a would simply ride upon the inclined face 61^a of the slide 61, thus allowing said slide 61 to be moved outwardly to its fullest extent without in any way transferring motion to the slide 63. 45 Hence as the movement of slide 63 is necessary to transfer motion to the guard or table for the reception of cigars to be discharged no cigars could be ejected from the machine and the attempt to operate the machine upon 50 the deposit of such a coin would be defeated. It will thus be seen that the element 58 forms a power-applying device and the element 63 a power-transmitting device, while the coin-slides interposed between them constitute an 55 automatic multiple clutch or selective device to vary the degree of motion of the said power-transmitting device under a determined range of motion of the said power-applying device.

60 An edge ion-slot 98 opens into the receiving-compartment 44 and is in communication with the front portion of the guide for the slides immediately below the chute 65. The purpose of this slot is to provide for the education of a coin when the vending mechanism

is not properly set. If the slide 58 should not be returned to its normal position—that is, fully retracted—the coin instead of dropping into the slot 59' would fall into the guide in front of said slide, and upon an attempt to operate the handle 33 the slide 58 on moving back would forcibly eject the coin through the slot 98 into the receiving-compartment 44, allowing the customer to recover his money and to insert it into the slot 18 for proper operation 75 of the apparatus.

The vending mechanism embodies means for regulating the discharge of goods from the two compartments according to the denomination of a coin inserted in the slot 18, which 80 coin may be usable for the purchase of goods from either compartment. Thus it is necessary to prevent the operation of the machine for the discharge of goods from the ten-cent compartment 8 when a nickel only is inserted 85 and which is adapted only for the purchase of one cigar from the compartment 7. It is also necessary to provide for the discharge of one cigar from the compartment 8 or two from the compartment 7 when a dime is inserted. 90

It is further necessary to provide means permitting of the discharge of five cigars from the compartment 7 or only three from the compartment 8 when a quarter is inserted. To these ends I have provided means for automatically regulating the movement of the guard or table to a different extent upon the deposit of a coin of a certain denomination when the operating-handle 33 is moved to the left or right. The shaft 46 is provided with a head 99, which fits within a slot 100, formed within a plate 101, pivoted to a shipper-arm 102, pivoted at its lower end to a bracket 103 upon the base 40 and forked at its upper end to engage a grooved collar 104 on the shaft 105 73, which shaft is mounted to slide longitudinally of its length or transversely of the frame in bearings 105 on the side walls 41 of said frame. A spring 106 bears upon the plate 101 and maintains the same in a yielding-like 100 engagement with the head 99, allowing said head to impart motion to the shipper-arm without undue strain upon the parts. When the shaft 46 is turned to the right by a corresponding movement of the handle 33, the shipper-arm 102 is swung by the head 99 to the right to slide the shaft 73 to the right, and when, on the other hand, the handle 33 is turned to the left the shaft 46 will also be moved to the left and the head 99 will swing the arm 102 to the left to correspondingly move the shaft 73. 110

The wheel or disk 74 on the shaft 73 is of much greater diameter than the wheel or disk 75 on the shaft 76, and on the periphery of said wheel 74 are teeth *a*, *b*, *c*, *d*, and *e*, five in number, arranged equidistantly, the teeth *b*, *c*, and *d* extending entirely across the periphery, while the teeth *a* and *e* are half or mutilated teeth and extend only approxi- 125 130

mately half-way across. The wheel 75 is in the nature of a star-wheel, being provided with a corresponding number of teeth—that is, five, adapted to coöperate with the teeth *a*, *b*, *c*, *d*, and *e* of the wheel 74. Normally the parts are in the position shown in Figs. 8 and 12, with the two wheels 74 and 75 in alinement; but when the handle 33 is turned to the right the shaft 73 is shifted to the left, so as to bring all the teeth *a*, *b*, *c*, *d*, and *e* into position to successively engage the teeth of the wheel 75 and transfer motion to the shaft 76 to operate the tray or table. When, on the other hand, the shaft 46 is turned to the right by the handle 33, the wheel 74 is shifted to the right a distance equivalent to one-half the thickness of the wheel 74, thereby throwing the two teeth *a* and *e* out of alinement with the wheel 75, so that as the wheel 74 turns the teeth *a* and *e* will not engage the wheel 75, while the operation of the teeth *b*, *c*, and *d* in engaging said wheel 75 will not be affected. Hence it will be understood that when a five-cent piece is inserted in the machine and handle 33 is turned to the right the vending mechanism will be operated to move the slide 63 and transfer motion to the shaft 73, which will turn the distance of one tooth, thereby causing the mutilated tooth *a* to engage and turn the wheel 75 the distance of one tooth, effecting the movement of the tray or table a sufficient distance to bring one of the receiving-openings of its grated portion in a position to receive one cigar. If upon the insertion of a nickel the handle 33 had been turned to the left, the guard or table would not be moved, for the reason that the gear 74 would be shifted to the right out of the path of wheel 75, so that upon the turning of gear 74 the wheel 75 would not be operated, and consequently could not transfer motion to the guard or table. If a ten-cent piece is deposited and the handle 33 is moved to the right, the movement of the slide 63 twice the distance would cause the movement of the gear 74 a distance of two teeth, whereby the gear 75 would be correspondingly moved and would operate the guard or table a distance to bring two of its receiving-openings beneath the grating in the cover 9, allowing two cigars to be discharged from the chamber 7. If, on the other hand, the handle 33 has been turned to the left on the deposit of a ten-cent piece, the shifting of the gear 74 to the right would move the tooth *a* out of position to engage the wheel 75. Hence only the tooth *b* would engage the wheel 75 and the guard or table would be moved only one-half the distance than that afforded by the movement of the handle to the right, so that but one cigar could be obtained from the compartment 8 for the sum of one dime, whereas two cigars could be obtained from the compartment 7 for the same sum. Upon the insertion of a

quarter into the machine and the turning of the handle to the right all the teeth a , b , c , d , and e will be caused to engage and turn the wheel 75 by the movement of the slide 63 to its fullest extent. Hence the wheel 75 would move the distance of five teeth, or make one complete revolution, thereby moving the guard or table its fullest extent and bringing its entire grated portion beneath the grating in the cover 9, allowing five cigars to be placed therein from the compartment 7. The turning of the handle 33 to the left, however, upon the deposit of a quarter would result only in the movement of the guard or table to a position to enable but three cigars to be discharged from the compartment 8 as the gear 74 would be shifted to the left, thus moving both teeth a and e out of the path of the wheel 75, so that the teeth b , c , and d would communicate motion to said wheel, moving it the distance of three teeth, or sufficient to operate the guard or table to bring three of its receiving-openings beneath the grating in the cover 9. Hence it will be seen that the deposit of a coin of certain denomination—say one dime—will enable a certain number of goods to be obtained from one compartment and a different number from the other compartment, and the insertion of a coin of another denomination—say a nickel—will permit of the discharge of one cigar from one compartment, but will enable no goods to be obtained from the other compartment.

From the foregoing description, taken in connection with the accompanying drawings, the construction and mode of operation and the advantages of the invention will be readily understood, and it will be seen that the construction is such as to enable a customer to visually inspect and make a selection of the goods on sale without actual manual contact therewith and without the possibility of surreptitiously removing any of the goods. 100 105

The invention is further advantageous in that it fully complies with all of the requirements of the revenue laws with reference to sale of cigars from the boxes in which they are packed and in that provision is made for dispensing one or more of a number of different brands of cigars or goods, according to the value or price thereof and the amount of money deposited in the machine. 110 115

It will of course be understood that but a single compartment may be employed and that the construction, arrangement, and general combination of elements may be changed or varied to a considerable extent within the scope of the invention and without departing from the spirit or sacrificing any of the advantages thereof.

Having described my invention, I claim--
1. A vending apparatus comprising a goods-compartment having an opening for the insertion of the hand, a flexible pocket guarding said opening, coin-controlled mechanism gov- 130

erning the discharge of goods from said compartment, and a shutter closing said opening and adapted to be opened when the coin mechanism is actuated to permit access to said pocket, substantially as described.

2. A vending apparatus having containers for goods of different values, a prime operating device, coin-controlled mechanism including a discharge device and a governor or regulator therefor embodying clutch members differently coupled by the deposited coins and set in action upon the manipulation of said operating device to govern the discharge of more or less goods from one or the other of said containers according to the denomination of the deposited coin, said mechanism being controllable by the one operating device to discharge goods from either container, and means for preventing the feed of goods from one compartment where the deposited coin is useful only to obtain goods from the other compartment.

3. In a vending apparatus, the combination with a plurality of goods-holders, of coin-controlled discharge mechanism comprising means including clutch members differently coupled and set in action by deposited coins of different values for effecting the discharge of a greater or less quantity or number of goods from either one of the goods-holders according to the value of the deposited coin, said means embodying a selective device automatically adjustable to effect delivery from either goods-holder for some coins but only from one of the goods-holders for other coins, and setting mechanism for preventing the discharge of goods from one goods-holder when the coin deposited is usable only in the purchase of goods from another goods-holder, substantially as described.

4. A coin-controlled mechanism adapted to control the feed of goods from a plurality of goods-holders, and to feed only from a certain holder for some coins, but to feed from either holder for other coins, said mechanism comprising a device for controlling the discharge of the goods, said device having a variable adjustment for discharging more or less goods, an operating device having a plurality of movements, coin-governed mechanism operable by said operating device upon the deposit of a coin to adjust said discharge-controlling device, said mechanism including means regulated by the value of the deposited coin for varying the operation of the coin-governed mechanism to set the discharge-controlling device to obtain different quantities of goods from any one goods-holder upon the deposit of coins of different values, means for preventing the discharge of goods from one goods-holder when the coin deposited is usable only to obtain goods from the other goods-holder, and means for regulating the operation of the coin-governed mechanism to enable different grades or quantities of goods to be obtained

from said goods-holders upon the deposit of a coin usable alike for the purchase of goods from any one of the goods-holders, and under different movements of the one operating device, substantially as described.

5. A vending apparatus comprising a goods-compartment having an opening for the insertion of the hand therein, a flexible pocket guarding said opening, coin-controlled mechanism governing the discharge of goods from the receptacle, a shutter closing the opening, an operating-lever for operating said vending mechanism, toggle-levers connected to the shutter, means for extending said levers, and means carried by the operating-lever for actuating said extending means, substantially as described.

6. A vending apparatus comprising a goods-compartment having an opening for the insertion of the hand therein, a flexible pocket guarding said opening, coin-controlled mechanism governing the discharge of goods from the receptacle, a shutter closing the opening, an operating-lever for operating said vending mechanism, toggle-levers connected to the shutter, bars geared to rise and fall and extend and contract said levers, a rod connected to operate the bars, and a cam carried by the operating-lever to actuate said rod, substantially as described.

7. A vending apparatus comprising separate goods-compartments, each having an opening, a flexible pocket guarding each opening, a shutter closing each opening, coin-controlled vending mechanism governing the discharge of goods from both compartments, and an operating device operable in one direction to open the shutter of and discharge goods from one goods-compartment and in a different direction to open the shutter of and discharge goods from the other compartment, substantially as described.

8. A vending-machine, having a plurality of goods-compartments and a coin-controlled apparatus for governing the feed of goods from said compartments, said apparatus comprising discharge mechanism, devices governed by the value of the deposited coin and controlling said discharge mechanism to effect the discharge of a greater or less quantity or number of goods from either of the compartments, and means coacting with and controlling said devices to regulate the discharge mechanism to effect delivery from either compartment for a certain coin or coins but only from one of the compartments for a different coin or coins, substantially as described.

9. A coin-controlled vending apparatus provided with a plurality of distinct compartments for vending goods of different values, delivering means, means governing said delivering means to enable goods to be obtained from any one of said compartments, and further means differently regulated automatically by different coins and controlling said gov-

erning means to enable different quantities of goods of any one kind or value to be obtained from a desired one of the compartments, or different values of goods to be obtained from the different compartments, upon the deposit of coins of different values, substantially as described.

10. A coin-controlled vending apparatus provided with a plurality of goods-holders, feed mechanism adapted to feed from any one of the holders, a governor variably regulated by coins of different values to control said feed mechanism to effect the feed thereby of more or less goods, an operating device for 15 operating the feed mechanism through the governor, and shifting means governed by said operating device whereby the feed mechanism may be manually controlled to feed from any desired one of the holders, at the option 20 of the customer, substantially as described.

11. A vending apparatus comprising a goods-compartment provided with an outlet, a reciprocating controlling device having a series of openings or pockets regulating the 25 number or amount of goods which may pass at one time to said outlet, means permitting the customer to visually inspect and select the goods and place the same in position for discharge, an operating device, and mechanism actuated by said device and controllable by coins 30 of different denominations to adjust said reciprocating controlling device to a greater or less extent to regulate the discharge of goods to the number or quantity purchasable by the 35 denomination of coin inserted, substantially as described.

12. A vending apparatus having a plurality of goods-holders, and coin-controlled mechanism adapted to feed only from a certain holder 40 for some coins, but adapted to feed from either holder for other coins, said mechanism including an operating device having two movements, a compound clutch comprising co-operating elements variably coupled by different 45 coin coins, a discharge device and a controller shiftable under the two movements of the operating device for imparting different movements to the discharge device under similar movements of the clutch, substantially as described.

13. A cigar-vending apparatus having compartments for cigars of different values, a controlling device having a series of openings or pockets regulating the number of cigars which 55 may discharge at one time from either compartment, means permitting a customer to visually inspect and select his cigars and place them in said openings or pockets, an operating device, mechanism operable upon the deposit of a coin and the movement of said operating device to adjust said controlling device to bring a greater or less number of openings into position to receive cigars, said mechanism being variably adjustable upon the insertion of coins of different denominations to 60 guard comprising an operating device

so adjust said controlling device, and means operable by the movement of said operating device in one direction or the other to afford access to either compartment exclusively of the other and regulate the adjustment of said controlling device so that a different number of openings will be brought into operative position by the movement of the operating device in one direction or the other, thereby enabling a different number of cigars to be obtained from each compartment upon the insertion of a coin of a prescribed value usable to purchase cigars from either compartment, substantially as described.

14. A cigar-vending apparatus comprising compartments adapted to contain goods of different values, each compartment having an opening and a flexible pocket guarding the same and adapted for manipulation, substantially as described, a shutter closing access to each pocket, a discharge-opening common to said compartments, a movable guard or controlling device for said discharge-opening, coin-governed mechanism, controlling said guard, to regulate the removal of goods from the compartments, and means adjustable in different directions to open one or the other of the said shutters and simultaneously adjust the coin-governed mechanism to set the said guard or controlling device to permit of the discharge of goods from the compartment whose flexible pocket is exposed by the opened shutter, substantially as described.

15. A vending apparatus comprising a casing divided to form compartments, and having an inlet to each compartment and a discharge-opening common to the compartments, a discharge device controlling said opening and also common to and accessible from the compartments, a flexible pocket for each inlet, coin-controlled mechanism for actuating the discharge device, and shutters normally closing access to said pockets, said shutters being controlled by said mechanism to admit access to either pocket at will, but only to one pocket and compartment at a time, substantially as described.

16. A vending apparatus, having a plurality of goods-compartments, and coin-controlled mechanism governed by the deposit of coins of different values to effect the discharge of a greater or lesser quantity or number of goods according to the value of the coin, said mechanism having means automatically controlled and regulated by the coin to effect the delivery of goods from either compartment when coins of the same value are applicable for the purchase of goods from either, and means coacting with said mechanism for preventing the discharge of goods from one compartment when the coin deposited is usable only in the purchase of goods from another compartment.

17. A coin-controlled vending apparatus provided with a plurality of distinct compart- 130

ments for containing goods of different values, delivering means, means governing said delivering means to enable goods to be obtained from any one of said compartments, and further means controlling said governing means to enable different quantities of goods of any one kind or value to be obtained from a desired one of the compartments, or different values of goods to be obtained from the different compartments upon the deposit of coins of different values, substantially as described.

18. In a coin-operated vending apparatus, and in combination with a variably-movable guard controlling a discharge-outlet, means for imparting different degrees of motion to said guard comprising a pair of slides one adapted to receive motion from an operating device and the other to transmit motion to the guard, and a series of intermediate slides, said slides having coin-receiving slots, the first-named slide and the intermediate slides being adapted to be connected by the coins, and operating means between the intermediate slides and the guard-operating slide, where by the insertion of different coins causes the intermediate slides to transmit different degrees of motion to the guard-operating slide, substantially as described.

19. In a coin-operated vending apparatus, and in combination with a variably-movable guard controlling a discharge-outlet, means for imparting different degrees of motion to said guard comprising a pair of slides one adapted to receive motion from an operating device and the other to transmit motion to the guard, and a series of intermediate slides, said slides having coin-receiving slots, the first-named slide and the intermediate slides being adapted to be connected by the coins, and said intermediate slides having shoulders at different points, and a pawl carried by the guard-operating slide to engage said shoulders, whereby the insertion of different coins causes the intermediate slides to transmit different degrees of motion to the guard-operating slide, substantially as described.

20. A vending apparatus having, in combination, a goods-compartment provided with a discharge-opening, a guard controlling the removal or discharge of goods through said opening, coin-controlled means for operating the guard, a power-transmitting slide adapted to operate the guard, and three intermediate slides, said slides having coin-receiving openings and the upper and lower intermediate slides having shoulders at different points and the central intermediate slide and inclined surface, and a dog upon the power-transmitting slide co-operating with said shoulders and inclined surface, substantially as described.

21. In a vending apparatus, the combination with a goods-compartment provided with a discharge-opening, and a variable adjustable guard therefor, of means for operating the guard, comprising an operating-shaft pro-

vided with a gear, a second shaft also provided with a gear, means for communicating motion from said second shaft to the guard, an operating-slide provided with rack-teeth meshing with the first-named gear and having a coin-slot and ratchet-teeth, a pawl adapted to engage the ratchet-teeth to prevent retrograde movement of said slide when released before completing its stroke, a power-transmitting slide also provided with a coin-receiving opening and with rack-teeth meshing with the gear on said second shaft, intermediate slotted slides provided with shoulders, and a pawl on the power-transmitting slide to engage said shoulders, substantially as described.

22. In a vending apparatus, a goods-compartment formed with a discharge-aperture, a variably-adjustable guard controlling the same, a guideway, upper and lower slotted coin-slides movable therein, said slides adapted, respectively, to operate the guard and receive motion from a prime operating device, intermediate slides having different degrees of movement, and means for connecting one or more of said intermediate slides with the upper and lower slides to impart greater or less movement to the guard upon the deposit of different coins, substantially as described.

23. Coin-controlled vending mechanism, comprising a goods-discharge device, an operating device, and an interposed-coating selective device, said selective device embodying a set or series of slides automatically governed by coins of different values to set the discharge device to discharge more or less goods according to the value of the deposited coin, said-selective device being adapted to cooperate with at least two coins of different sizes, and means forming part of said selective device for preventing transfer of motion to the said discharge device when a certain coin of an intermediate size is deposited, substantially as described.

24. In a vending apparatus, the combination with a goods-compartment provided with a discharge-opening, of a variably-adjustable guard controlling said opening, an operating device, a shaft operated thereby, coin-operated means embodying a member operated by the shaft, a power-transmitting member, and devices controlled by the deposit of coins of different denominations for transmitting different degrees of motion to said power-transmitting member, and means operated by said power-transmitting member for imparting a determined variable movement to the guard, substantially as described.

25. A vending apparatus having goods-compartments separated from each other but provided with a common discharge-opening, a variably-adjustable guard for said opening having a series of pockets or openings, an operating device, coin-controlled means, actuated by said operating device and embodying a power-transmitting member having a

variable movement according to the denomination of the deposited coin, and means operated by said power-transmitting member for imparting motion to the guard, said means adjustable to vary the extent of movement communicated to the guard according to the direction of movement of the operating device, whereby different quantities of goods may be obtained from the compartments upon the deposit of a coin of a certain denomination or value, substantially as described.

26. A vending apparatus having goods-compartments separated from each other but provided with a common discharge-opening, a variably-adjustable guard for said opening, an operating device having two operative movements, coin-controlled means set in motion by the operating device and having a power-transmitting member movable therewith upon the deposit of a coin, and means actuated by said power-transmitting device to operate the guard, said means adapted to impart different degrees of movement to the guard under the different operative movements of the operating device, substantially as described.

27. In a vending apparatus, goods-compartments separated from each other but having a common discharge-opening, a variably-adjustable guard therefor, a rock-shaft, a handle for operating the rock-shaft in either direction, a mutilated gear upon said shaft, a counter-shaft carrying a pair of pinions to mesh with said gear, a pair of shafts carrying toothed wheels, one of said wheels having full and half teeth, means for operating the guard from the other shaft, means operated by the rock-shaft for shifting one of said wheels relative to the other wheel, and coin-controlled means operated from the counter-shaft and having a member operable upon the deposit of a coin to communicate motion to the first-named wheel-shaft, substantially as described.

28. In a vending apparatus, goods-compartments having a common discharge-opening, a guard for said opening variably adjustable to regulate the number of articles or amount of goods discharged, three shafts, one being an actuating rock-shaft, the second an operating-shaft for the guard, and the third an intermediate shaft operated from the rock-shaft and adapted to transmit motion to said guard-operating shaft, a cam upon the rock-shaft, a wheel or disk upon the intermediate shaft provided with full and half teeth, a second wheel or disk upon the operating-shaft and adapted to receive motion from the first-named wheel or disk, means operated by the cam to shift one of said wheels relative to the other wheel, and coin-controlled means for regulating the action of the gearing between the rock-shaft and intermediate shaft, substantially as described.

29. Coin-controlled vending mechanism, comprising a plurality of goods-containers,

each provided with an inlet, shutters controlling said inlets, a discharge device common to the several containers, an operating device, means operated by said operating device to actuate said discharge device, said means including a selective device embodying a set or series of members automatically governed by coins of different values to cause said operating means to set the discharge device to discharge more or less goods according to the value of the deposited coin, and connections between the operating device and shutters, whereby reverse movements of said operating device will give access to one container and close access to the other container, and vice versa, substantially as described.

30. In a vending apparatus, goods-compartments provided with a common discharge, a variable adjustable guard for said discharge, a rock-shaft, means for transmitting motion thereto, a second shaft for operating the guard, a counter-shaft, coin-controlled gearing between the rock-shaft and counter-shaft, a wheel or disk upon the counter-shaft provided with full and half teeth, a co-operating wheel or disk on the guard-operating shaft, a shifter-arm for shifting one of said wheels relative to the other wheel, a cam upon the rock-shaft, and a pivoted slotted plate carried by the arm and acted on by the cam, substantially as described.

31. A vending apparatus having a power-transmitting device, coin-controlled vending mechanism including a governor having a variably-operable compound clutch coupled and set in action by the deposited coin for imparting more or less movement to said power-transmitting device according to the value of the deposited coin, said clutch being adapted to co-operate with at least two coins of different sizes, a discharge device automatically opened and closed by the said power-transmitting device, and means for preventing operation of the clutch to set the discharge device into action upon the deposit of any certain coin of intermediate size, substantially as described.

32. In a vending apparatus having a plurality of goods-holders, coin-operated mechanism comprising means for controlling the discharge of goods from either goods-holder, coin-governed mechanism for imparting a variable movement thereto, an operating device for imparting movement to said coin-governed mechanism upon the deposit of a coin, means for effecting an automatic variable action of said coin-governed mechanism upon the deposit of coins of different denominations to effect a corresponding movement of the means controlling the discharge of the goods, whereby a different number of goods may be obtained from one compartment upon the insertion of coins of different values, and different grades of goods may be obtained from the plurality of compartments upon the deposit

of any one certain coin, and further means for preventing the discharge of goods from one compartment upon the deposit of a coin usable to purchase goods only from the other compartment, substantially as described.

33. A vending apparatus having a plurality of goods-holders, an operating device, and coin-controlled mechanism having a differential controller actuated by the operating device to govern the discharge of goods, said differential controller being governed automatically by the deposited coins and normally arranged to operate under different operative movements of said operating device to feed only from a certain holder for a certain coin or coins, but to feed from either holder for a different coin or coins, substantially as described.

34. A vending apparatus, having a plurality of goods-compartments, in combination with an operating device manually manipulative to different positions, and coin-controlled mechanism governing the discharge of goods from said compartments, said mechanism being adjustable under one movement of the operating device to effect the discharge of goods from one compartment and under a different movement of said operating device to effect the discharge of goods from another compartment, substantially as described.

35. A vending apparatus, having a plurality of goods-holders, and coin-controlled mechanism having a selective device for controlling the delivery of more or less goods from either holder for coins of different values, and for effecting the delivery of different quantities of goods from different holders for coins of like values.

36. A vending apparatus, having a plurality of goods-holders, and coin-controlled mechanism having feeding means and controlling devices adapted to feed from a certain holder for certain coins and interchangeably from either holder for other coins and to feed a variable amount of goods in either case according to the denomination of the coin, substantially as described.

37. A vending apparatus, having a goods-compartment provided with a discharge-outlet, a guard therefor variably adjustable to control the number or amount of goods removable through the outlet, and coin-controlled mechanism for adjusting said guard, said mechanism comprising means for moving said guard, an operating device, a series of intermediate slides, co-operating means between the slides, operating device and guard-moving means, whereby the insertion of different coins connects the said guard-moving means with the operating device through the slides to transmit different degrees of movement to said guard-moving means, and a clutch connection between certain slides for preventing a certain coin of intermediate value from coupling said slides to impart movement to

the guard-moving means, substantially as described.

38. A vending apparatus, having coin-controlled mechanism embodying a governor for transmitting variable movement to a discharge device, said governor comprising superposed slides having coin-slots, two or more of said slides adapted to be coupled by coins of different sizes entering said slots, and means for preventing the coupling of the slides and operation of the discharge device upon the inlet of any certain coin of an intermediate size.

39. In a vending apparatus, the combination of a plurality of goods-holders, a discharge device, coin-controlled mechanism for governing the discharge device to control the discharge of goods from the holders, said mechanism comprising an operating device for the said discharge device, and a selective device consisting of conjunctively-related clutch elements adapted to be variably coupled by deposited coins of different values for automatically governing the said operating device so as to adjust the discharge device to discharge more or less goods from either of the goods-holders proportionate to the value of the deposited coin, setting means for adjusting said coin-controlled mechanism to effect the delivery of goods from either goods-holder for some coins but only from one of the goods-holders for other coins, and means coacting with said setting means for preventing the discharge of goods from one goods-holder when the coin deposited may be applied only to the purchase of goods from another goods-holder, substantially as described.

40. A vending apparatus having a controller for governing the motion of a discharge device to deliver more or less goods, said controller consisting of independent members having different degrees of motion, said members being provided with means for engagement by coins of different values, whereby various coins may couple the independent members to secure a variable range of motion of said controller, substantially as described.

41. A vending apparatus having a goods-compartment provided with a discharge-opening, a guard controlling said opening and adapted to be adjusted to present one or more passages for discharge of one or more articles through said opening, means for permitting a customer to make a selection of goods within the compartment and transfer the same to said passages without possibility of surreptitiously removing the goods, a closure adapted when opened to permit access to such means, a selective device governed by the coins to impart a variable movement to the guard upon the deposit of coins of different values, and coin-controlled mechanism governing both the closure and the selective device, substantially as described.

42. A vending-machine having a goods-compartment provided with a discharge-out-

- let, a guard controlling said outlet, means for permitting a customer to have access to the compartment to make a selection of goods from a store within the compartment and 5 transfer the same for discharge when the outlet is opened by the guard without possibility of surreptitiously abstracting such goods, such means normally preventing such access, and coin-governed mechanism adapted upon 10 the deposit of a coin to permit operation of such means and adjust the guard for discharge of the selected goods, substantially as described.
43. A vending-machine comprising a goods-compartment having a discharge device and an opening for insertion of the hand, a flexible pocket guarding said opening, a door or shutter controlling access to the pocket, and coin-governed mechanism controlling the operation of the discharge device and door, substantially as described.
44. A vending-machine having a differential, automatically-adjustable controller for governing the operation of a discharge device, 15 said controller consisting of a series of elements having different ranges of motion, means whereby the said elements are adapted to be differently and positively coupled by coins of different values and means whereby when a 20 determined motion is imparted to one of such elements a range of operating motion variable proportionately to the value of the coin will be imparted to another element through the medium of a differential adjustment of the intermediate or intervening elements, substantially as described. 35
45. In a coin-controlled vending apparatus, the combination of a casing having a plurality of independent goods - compartments, discharge mechanism, coin-governed mechanism for operating said discharge mechanism upon the deposit of a coin, shifting mechanism controllable for regulating the action of the coin-governed mechanism to enable goods to be discharged from either compartment at 40 the option of the customer, and a differential controller for regulating said coin-governed mechanism to allow different quantities of goods to be obtained from either compartment, said controller being governed by the 45 deposited coins according to the value or denomination thereof to differentially adjust said discharge mechanism, substantially as described. 50

In testimony whereof I affix my signature in presence of two witnesses.

DAVID K. JACKMAN.
